CLAIM

The ornamental design for a decorative film as shown and described.

DESCRIPTION

FIG. 1 is a front view showing the new design for a decorative film;

FIG. 2 is a rear view thereof;

FIG. 3 is a left side view thereof;

FIG. 4 is a right side view thereof;

FIG. 5 is a top plan view thereof;

FIG. 6 is a bottom view thereof;

FIG. 7 is a front left top perspective view thereof;

FIG. 8 is a front right top perspective view thereof;

FIG. 9 is a front left bottom perspective view thereof;

FIG. 10 is a front right bottom perspective view thereof; and,

FIG. 11 is an enlarged detail view taken at portion 11-11 of FIG. 1.

The broken lines shown in FIGS. 2-10 indicate portions of the decorative film and form no part of the claimed design. The broken lines shown in FIG. 1 are included to define the area at which the enlarged detail view is taken and form no part of the claimed design. The broken lines shown in FIG. 11 shows borders of the enlarged detail view and form no part of the claimed design.

1 Claim, 8 Drawing Sheets
